(57) **CLAIM**

The ornamental design for a surface configuration of a rear bumper for a vehicle, as shown and described.

DESCRIPTION

FIG. 1 is a right perspective view of a surface configuration of a rear bumper for a vehicle according to my novel design; FIG. 2 is a front view of the surface configuration of a rear bumper for a vehicle according to my novel design; and, FIG. 3 is a right side view of the surface configuration of a rear bumper for a vehicle according to my novel design. The broken lines are for illustrative purposes only and form no part of the claimed design. Enclosed is a set of photographs of an embodiment of the invention.
